PAD HOLDER

Jacob S. Sherman, Chicago, Ill., assignor to Park Sherman Company, Chicago, Ill., a corporation of Illinois

Application June 24, 1955, Serial No. 36,680

Term of patent 14 years

(Cl. D74—1)

Fig. 1 is a top plan view of a pad holder embodying my new design;

Fig. 2 is a side elevational view of one of the two like sides thereof.

Fig. 3 is a plan view of the undersurface of the cover portion shown in Fig. 1 as it appears apart from the pad; and

Fig. 4 is an end elevational view thereof.

The essential features of the design reside in the cover portion shown in solid lines on the drawing.

I claim:

The ornamental design for a pad holder, substantially as shown and described.
